Primary Examiner — Keli L Hill*Assistant Examiner* — Sara S Sahneh(74) *Attorney, Agent, or Firm* — Novick, Kim & Lee, PLLC; Sang Ho Lee; Hyun Woo Shin(57) **CLAIM**

We claim the ornamental design for a digital door lock, as shown and described.

DESCRIPTION

FIG. 1 is perspective view of a digital door lock, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the drawings from an unclaimed boundary, and form no part of the claimed design.

1 Claim, 6 Drawing Sheets(56)
